Des. 214,880
Patented Aug. 12, 1969

214,880

END CLOSURE FOR A CONTAINER

Frederick J. Stec, Oak Lawn, Ill., assignor to Continental Can Company, Inc., New York, N.Y., a corporation of New York

Filed Mar. 11, 1968, Ser. No. 10,908

Term of patent 14 years

Int. Cl. D9—02

U.S. Cl. D9—255

FIG. 1 is a top plan view of an end closure for a container and opener therefor embodying my new design;

FIG. 2 is a bottom plan view, and

FIG. 3 is an edge view thereof.

I claim:

The ornamental design for an end closure for a container, as shown.
